UNITED STATES PATENT OFFICE

WILLIAM H. SOMMER, OF PEORIA, ILLINOIS

HEATING APPARATUS

Original application filed April 10, 1926, Serial No. 101,130. Divided and this application filed June 26, 1928. Serial No. 288,486.

This invention has reference to new and useful improvements in heating apparatus and it has special reference to hot-water heaters designed for the efficient and economic consumption of fuel in the heating of dwellings.

This invention has for one of its objects an improved construction of hot-water heater, including a boiler of the vertical type, the 10 combustion chamber of which is formed by a wall of fire-brick encased in a wall of insulating brick, surrounding which is a water jacket, the water being heated, reaching its highest temperature at the top of the boiler, and connected with the top of the boiler is a 15 housing or flue chamber enclosing a plurality of flues and said housing and flues extend laterally from the top of the boiler and are directed downwardly therefrom to provide a 20 down draft; a common inlet being provided for the water directed to the water jacket and to the housing surrounding said flues, the direction of movement of water in said housing being towards the top of the boiler, with 25 outlets from said boiler and housing in communication with a header or manifold from which the hot-water is conducted to the usual radiators; the boiler and housing for the flues constituting a substantially inverted U, and 30 the arrangement of the flues being such that by the provision of a clean-out opening at the top of the boiler access may be easily had to the flues for cleaning the same.

The invention has for a further object the 35 use of gas as a fuel and to provide a supply line to the burner within the boiler; said supply line being preferably intercepted at one point by a thermostat having communication with a room of a dwelling and adapted 40 through valve means to control the amount of gas conducted to the boiler in direct proportion to the temperature of the room; said supply line being further intercepted by a 45 thermostat associated with said header or manifold and having valve means adapted to take up the lag, due to the increased temperature of the water and the slower increase in temperature of the room in which the said first mentioned thermostat is located; and 50 said supply line being connected preferably

at the boiler by a gas operated air regulating valve for controlling the admission of air and the proper mixture of the latter with the gas emitted to the burner. While I have elected to show means for burning gas as 55 fuel, and conducting means therefor, the heater structure is such that oil may be used as the fuel, if it is so desired.

Further objects will more fully appear from the following description taken in connection with the accompanying drawings, in which I show a preferred embodiment of the invention, wherein:

Fig. 1 shows in side elevation and on a 60 greatly reduced scale a heating apparatus embodying my invention;

Fig. 2 shows on a somewhat larger scale and partly in cross-section the gas line, burner, thermostatic controls and the gas operated air regulating valve and air mixing 65 chamber, part of the heating apparatus and dwelling being shown in dotted lines;

Fig. 3 is a detail in plan and cross-section as the same would appear if taken on the line 70 3—3, Fig. 2;

Fig. 4 is a face view of the head of the 75 adjusting screw for the thermostat communicating with a room of a dwelling, and is designed to show a gauge which may be used thereon and is as the same would appear 80 in plan on the line 4—4, Fig. 2;

Fig. 5 is a face and side view of the 85 adjusting screw for the thermostat associated with the header or manifold, and is designed to show a gauge thereon and is as the same would appear in elevation on the line 5—5, Fig. 2, and

Fig. 6 is a sectional view of the parts, somewhat as shown in Fig. 2, except that the air regulating valve is operated electrically from a thermostat instead of being gas operated.

Like characters of reference denote corresponding parts throughout the figures.

The boiler 1 is preferably of the vertical type, being provided with a combustion 90 chamber 2, the immediate wall of which is made of fire-brick 3, and said chamber at its upper end opens into a supplemental chamber 4 through which the products of combustion pass, as indicated by the arrows 95 100

of direction on Fig. 1, and from thence said products of combustion pass into a plurality of spaced tubes 4', suitably arranged in relation to each other in a housing 5, forming the flue chamber. The fire-brick wall 3 of the combustion chamber is surrounded by or encased within an insulating brick wall 6, which in turn is encased within a metallic sheathing 7 between which and an outer cylindrical casing 8 is provided a water jacket 9. This water jacket 9 surrounds the combustion chamber 2 substantially throughout its length and below the bottom thereof and terminates in and communicates with a supplemental water jacket 10 which surrounds all but the front wall of the supplemental chamber 4 and overlies the same in the manner shown in Fig. 1. In what is designated as the front wall of the supplemental chamber 4 there is provided a gas tight door 11 by means of which access may be had to the upper end of the boiler, and in particular, the supplemental chamber 4 thereof, after first removing the insulating wall 11', whereby, to provide for the introduction of suitable flue cleaning means, for cleaning the several flues 4'. These flues, as indicated in Fig. 1, are of the down draft type and preferably extend laterally from the upper end of the boiler, horizontally for a short distance, and then by an easy curve extend down in the leg of the housing 5, opening at their lower ends into a flue box 12, which may have a suitable sewer connection for the removal or discharge of any water which may condense within said flues. The housing 5 has preferably a gas tight connection at 5' with the supplemental chamber 4 of the boiler.

The water jacket 9 of the boiler and the flue chamber of the housing 5 are connected and have communication with a water conducting pipe or header 13 extending therebetween; the main section of said pipe 13 being detachably connected to short sections 13' and 13'', connected, respectively, with the water jacket 9 of the boiler and the flue chamber of the housing 5, as best seen in Fig. 1, and said section 13 is arranged to have connected thereto and communicating therewith the main supply or return feed pipe 14, from which extend and to which are connected a plurality of pipes 15 connected at remote points with preferably radiators, not shown, located in respective rooms of a dwelling. The flue box 12 is shown connected to a chimney or a flue 8', through and by means of a pipe connection 15, having a depending air inlet leg 16 in which may be arranged, for adjustment, a damper, not shown, which may be set at any predetermined position, or so connected as to automatically maintain a definite amount of draft at all times, as will be understood. The use of such a valve, opened or closed, will determine and regu-

late the draft in the flue 8', and result or not in economical use of fuel.

Connected to the upper wall of the supplemental water jacket 10 of the boiler proper, and in communication with said chamber, is a pipe connection 18 and a like connection 19 is shown connected to the housing 5 adjacent the boiler and in communication with the flue chamber therein, and to said pipe connections 18 and 19 and in communication therewith are short legs 18' and 19', which form a part of or are connected to a preferably horizontally disposed header or manifold 20, provided with a supply line 21 leading to and suitably connected with radiators of the dwelling to which the hot water is to be supplied; thus the circulation of water from the water jacket 9, and from thence through the supplemental chamber 10 and from the flue chamber of the housing 5 passes into the header or manifold 20 and out through the supply line 21 to one or more radiators and from thence back through the plurality of pipes 15, in communication with the header or pipe 14, and from the latter back into the water jacket 9 and the flue chamber of the housing 5, through the connections 13, 13' and 13'', as will be readily understood.

For convenience in the erection of the heater, the boiler 1 and the housing 5 are separate elements and are adapted to be joined, the upper portion of the housing 5 to and within the supplemental chamber 4 at the upper end of the boiler; also, through the connection of the supply line sections of pipe 13, 13' and 13'', and by the attachment of the header or manifold 20 with the pipe connections 18 and 19, respectively, as previously described.

Extending through, what may be termed the front wall of the boiler, is a fuel-feed pipe 22 which terminates within the combustion chamber of the boiler and forms the burner having flame orifices 23, see Figs. 2 and 6. Said pipe 22 is connected exteriorly of the boiler with an elbow 24, the major portion of which is disposed vertically and comprises a mixing chamber 25 in which is located a fuel-nozzle or ejector 26, preferably formed integral therewith, and said fuel-nozzle or ejector and elbow constitute sections of a chambered casting 27, arranged in communication with the lower portion of the combustion chamber 2 below the burner, see Fig. 2. The casting 27 is formed or provided with a short vertically disposed cylinder 28 surrounded by a fuel chamber 29, the upper end of the cylinder being closed by a cap-plate 30 and the wall of the cylinder is provided with a plurality of fuel-feed orifices 31, providing means of communication between the interior of the cylinder 28 and the chamber 29, said last mentioned chamber by a suitably arranged duct 32 being in commu-

nication with the nozzle or ejector 26, disposed vertically within the mixing chamber 25. The cylinder 28 opens out of its lower end into a fuel-inlet chamber 33 with which is connected and has communication with a pipe section 34 to which is connected the main fuel-feeding line 35, being a pipe of any suitable dimensions. Within the cylinder 28 is operatively disposed a piston 36 which normally closes all of the orifices 31 in the wall of said cylinder against the passage of fuel therethrough and which is adapted to be raised by the pressure of the fuel entering the fuel-inlet chamber 33 from the line 35, whereby, more or less of said fuel is fed to the burner through the orifices 31, thence into the chamber 29 and from thence into and through the nozzle or ejector 26 into the burner pipe 22. The piston 36 is connected with a piston rod 37 which extends downwardly and through the lower wall of the fuel-inlet chamber 33 and to the lower end of said piston rod is connected a float member 38 operatively carried in a float chamber 39, which is adapted to contain mercury, or other liquid. Said float chamber 39 is preferably in the form of a short cylinder, open at its upper end, and is supported by and partially within a depending casing 40 suitably connected and supported by the chambered casting 27; the lower portion of said casing 40 being provided with air-inlet openings 41, through which air enters in the direction of the arrows shown in Fig. 2, and which finds circulation through the chambered casting 27 into the mixing chamber 25, to be mixed with fuel ejected through the nozzle 26, to provide a proper combustible and which, also, finds its way from said chambered casting 27 into the lower portion of the combustion chamber of the boiler to provide for the proper combustion of the burned fuel emitted from the burner 22, as will be understood. Connected with the piston rod 37 is an air-valve 42, normally resting on and providing a closure for the casing 40, and said valve is provided with two or more air openings 43 therethrough. With the construction as described, it should be obvious that, when the valve 42 is closed the openings 41 in the casing 40 and the openings 43 in the valve 42 always provide for the entrance of a small amount of air into the chambered casting 27, from which it may find its way through the mixing chamber 25 to the burner and into the combustion chamber of the boiler below the burner, and that with one of the orifices 31 in the cylinder 28 being always exposed a small amount of fuel may pass therethrough from the feed-line 35 through the fuel-feeding chamber 33 into the fuel-feeding nozzle 26 and from thence to the burner, whereby, providing there is fuel passing through the feed line 35, a pilot flame is always main-

tained at the burner 22. This inlet of fuel from the fuel-feed line 35 is increased from time to time, when the furnace is in full operation, where the admission of an additional quantity of fuel, acting upon the piston 36 releases more of the orifices 31, whereby, more fuel is admitted to the burner, which upward movement of the piston lifts the valve 42 and provides for a comparative increase of volume of air entering the chambered casting 27. As an additional controlling means for the amount of air admitted to the combustion chamber 2 of the boiler, I provide an adjustable valve member 27, within said chambered casting 27, located at or near the inner discharge end of said casting, or at the point where the air leaves the casting, to provide for the proper combustible mixture in the combustion chamber of the boiler. To permit access to be had to the burner 22 for ignition purposes, or for any other purpose, I provide in the front wall of the boiler, immediately above the burner, a gas tight doorway 22.

With the arrangement of the boiler and the flue chamber as shown, which includes the location of the feed water pipe to the water jacket of the boiler and to the housing enclosing the tubes in substantially the same plane with the point of discharge of the products of combustion from the flues and the location of the burner in the boiler, I provide not only for an efficient circulation of the water in the water jacket of the boiler and through the housing around the tubes, but I also provide for a more gradual raising of the temperature of the water, which reaches its highest maximum at the point of discharge of the water from the water jacket of the boiler and from the housing enclosing the tubes. Insulating the boiler as I do the water becomes more gradually heated as it reaches the compartment 4, and likewise the water conducted through the housing 5 becomes more gradually heated as it rises to the top thereof. At the points of egress of the water from boiler and housing the products of combustion are travelling counter thereto and at these points the highest temperature of the water is reached.

I provide in the fuel-feeding system two thermostatic controls; one a room thermostat, generally designated as 44, that operates in somewhat the usual manner of thermostats of this character, whereby, to increase the amount of fuel admitted to the burner of the boiler as the temperature in the room decreases, and the other generally designated as 45, which is associated with the header or manifold 20, which functions in a similar manner to the thermostat 44 and controls the temperature of the water passing through the header or manifold, the purpose of which, is to take up the lag by the increased temperature of the water and the slower increase in

temperature of the room in which the thermostat 44 is located. The thermostat 44 is connected with and intercepts the fuel feed line 35 at a suitable point in advance of the thermostat 45, and the latter is connected with and intercepts said fuel feed line 35 at a point adjacent the header or manifold 20 and is, therefore, located at a suitable point between the location of the thermostat 44 and the air controlling valve 42. At the point where the thermostat 44 intercepts the fuel feed line 35 a coupling 46 is provided. An opening therein, by means of which communication is provided between one section of the fuel feed line to the other, is controlled by a suitable valve 47, operable by an inactive part 44' of the thermostat 44, the latter being operable through and by means of an adjustable screw plate 48' provided with a suitable dial or gauge 49', see Fig. 4. This dial or gauge enables the setting of the valve 47 to the temperature which it is desired shall be maintained in the room of a dwelling, and when this temperature decreases the thermostat becomes automatically actuated in the usual manner to open the valve 47 to a greater extent, thereby, permitting a greater volume of fuel to pass through the fuel feeding line and the coupling 46 controlled by said valve 47. This valve is provided with a small orifice 48 therethrough, so that even though the valve may be closed, a constant supply of fuel, even of small volume, is passing through the system. The thermostat 45 differs only from the thermostat 44 in its detailed construction, the part to be affected by the temperature of the water being tubular and indicated at 50 and has an inactive part 49 disposed therewithin, the part 49 being suitably carried within the header or manifold 20. Such thermostat is provided with an adjustable screw 51, the face plate of which is provided with a dial or gauge 52, see Fig. 5, adapted to be set to the temperature of the water at which it is desired to be operated, and said adjustable screw 51 is arranged to actuate a valve member 52 controlling an opening in a coupling 53 which communicates with sections of the fuel feed line 35 and to which the same are connected, as best seen in Fig. 2, and said valve 52 is provided with an orifice 52' therethrough so that even though the valve may be closed a constant supply of fuel, even of small volume, is passing through the system. The shut-off valve designated 54 is preferably located in the fuel-feed line in advance of the coupling 46 which may be closed when the heating apparatus is in non-use and opened again when the boiler is to be fired.

I have only briefly described the characteristics of the two thermostats 44 and 45 as I am not concerned in the specific or detailed construction thereof, as I realize that modifications and changes may be made in

both of these thermostats and the means for controlling and operating the valves 47 and 52, respectively, without departing from the spirit and scope of the invention herein, and it is only necessary to say that the part 44' operatively connected with the valve 47 of the thermostat 44 and the part 49 in operative engagement with the adjusting screw 51 of the thermostat 45 are preferably of metal known as "invar", which is well understood by those skilled in the use of thermostats, to have an extremely small coefficient of expansion, hence these parts 44' and 49 are relatively inactive, while the parts 44 and 50 are formed of material having a large coefficient of expansion, and hence constitute the active parts of the two thermostats.

It will be apparent from the dual thermostatic control which I provide, one for a predetermined room temperature and one for a predetermined water temperature, that as a result of the adjustment of the two in relation to each other, I can automatically control the supply of fuel past the piston 36 to the burner, whereby, to maintain a more constant temperature of the water circulating through the hot water system. The thermostat 44 is directly affected by less temperature in the room, than the predetermined setting of such thermostat, and will automatically regulate the amount of fuel which is let into the system. When the water reaches its maximum temperature, fixed by the predetermined setting of the thermostat 45, the latter acts to retard the flow of fuel through the system and immediately when the temperature of the water is decreased below the predetermined setting of such thermostat 45 it automatically acts to allow for an increased volume of fuel passing through the system to the burner and as long as a predetermined temperature may be maintained in the dwelling, the lesser the amount of fuel permitted to pass the valve 47 controlled by the thermostat 44; but should this temperature reduce, then said last mentioned thermostat acts to permit a greater volume of fuel to be fed through the system, to be only checked by the thermostat 45, when the temperature of the water reaches the maximum amount fixed by the setting of the thermostat 45. Through this dual arrangement it should be obvious that a maximum temperature may be very easily and conveniently maintained with an economic use of fuel.

Irrespective of the temperature regulation or effectiveness of such temperature on the thermostat 44, which is located at a convenient point in a dwelling, it will be obvious that the resulting action on the thermostat 45 will be determined by the general temperature of the boiler water and may or may not be affected by what occurs in the area immediately adjacent to the thermostat 44.

In Fig. 6 a modification is shown in struc-

ture and operation of the valve mechanism for controlling the supply of fuel from the fuel feed pipe to the ejector and the admission of air to the chambered casting 27.

5 In Fig. 2 I show a floating piston and valve which are operated solely by the gas pressure which is set up in the fuel feeding chamber 33, whereas, the valve mechanism in Fig. 6 is actuated by electro-magnetic means from the room thermostat.

10 Reference being had to Fig. 6, the piston rod 37' has connected thereto the air valve 42' functioning substantially in the same manner as the air valve 42, and to the piston rod is connected a valve member 36' which controls a valve opening and is intended to function somewhat in the same manner as the piston 36, and said piston rod 37' has further connected thereto a core 55 operably carried in a solenoid 56, suitably supported by the chambered casting 27 and connected with said solenoid are the electrical conductors 57, which as shown lead to a suitable room thermostat 44" and to a suitable source 15 of electric current for the purpose of energizing and deenergizing the solenoid 56. With this arrangement there is obviated the thermostat intercepting the fuel feed line 35 as previously indicated at 44 and the thermostat 44" when it functions, as would the thermostat 44, directly actuates the valve means 36' and 42'. In every other respect the system is substantially as that indicated and described above. The valve member 36' has an opening 36" therethrough which permits a small quantity of fuel to be supplied through the system, in the manner above described, to provide a pilot flame at the burner at all times.

10 The arrangement of fuel controlling means shown on Fig. 2 has many advantages over the control of fuel shown on Fig. 6. In Fig. 6 the room thermostat electrically controls the fuel valve. It has only two positions: 15 closed tight or open wide. As compared to a fuel feeding device that would feed a constant amount of fuel per hour, the arrangement shown in Fig. 6 would have a given outside temperature, by burning one half of the time; the other half of the time the boiler is idle. It is well known that the more nearly constant a boiler is operating, the higher its efficiency will be. The arrangement of fuel valves in Fig. 2 permit, as nearly as it is possible to have, a constant amount of fuel going into the boiler at all times, for a given room and a given boiler water temperature.

15 This application is a division of the application filed by applicant April 10, 1926, bearing Serial No. 101,130 now Patent No. 1,694,191, dated December 4, 1928.

What I claim is:-

1. In combination with a boiler and a fuel burner, a single fuel supply conduit connected 20 to the burner, means connected to the conduit

and responsive to room temperatures to control the fuel entering the burner through said supply conduit, and means responsive to the boiler temperature and connected to the conduit for independently controlling the fuel entering the burner. 70

2. In combination with a boiler and a fuel burner, a source of fuel supply, means operable by the fuel pressure for controlling the amount of fuel fed to the burner, a thermostatic control for the pressure of the fuel, means to supply air to both the interior of the burner and exteriorly adjacent thereto, and means connected to and operable by said first named means for controlling said air supply 80 means. 75

3. In combination with a boiler, a casing having a cylinder, the walls of which are perforated, and having a channel surrounding the cylinder walls, a fuel nozzle communicating with the channel, a fuel burner enclosing the nozzle, said casing having an air conduit below the cylinder, which conduit communicates with the burner interior to supply air around the nozzle and having a part leading into the boiler below the burner to supply air to the latter, said casing having a chamber aligned with the cylinder and located therebelow and having an air inlet surrounding the chamber, a piston valve slidable in the cylinder, a valve connected to the piston valve for controlling said air inlet, a fuel supply connected to the casing for conducting fuel into the casing below the piston valve thereby to actuate same, and a thermostatic control for the fuel supply to regulate the action of the fuel on the piston valve thereby to control both the quantity of air entering the burner and boiler and the amount of fuel entering the burner. 90 95 100

4. In combination with a boiler having a fuel burner, a fuel supply pipe having a valve casing, a valve in said casing, a room thermostat connected to said valve for operating same, a header connected to the boiler and having a valve casing associated therewith, a valve in the last named casing, a boiler temperature controlled thermostat in the header connected to the last named valve for operating the latter, a pipe connecting said casings for conveying the fuel from the first to the second named casing, and a pipe connected to the second named casing and to the burner. 110 115

5. In combination with a boiler having a fuel burner, a single fuel supply conduit connected to the burner, a pair of spaced valves in said conduit, a room thermostat for controlling one of said valves, and a second thermostat influenced by the temperature of the boiler water for controlling the other valve. 120 125

6. In combination with a boiler, a casing having a burner connected thereto, a fuel nozzle in the burner connected to the casing, said casing having an air conduit to supply air into the burner and in surrounding rela- 130

tion to the nozzle and also to the boiler beneath the burner; a fuel supply connected to the casing, means operable by the pressure of the fuel for controlling the amount of fuel entering the nozzle, and means operable by said last named means for regulably supplying air to the conduit.
